UNITED STATES PATENT OFFICE.

LOREN W. RAY ANDRIST, OF MANKATO, MINNESOTA.

CAMPING ATTACHMENT FOR MOTOR VEHICLES.

1,426,031.

Specification of Letters Patent. Patented Aug. 15, 1922.

Application filed November 19, 1921. Serial No. 516,420.

To all whom it may concern:

Be it known that I, LOREN W. RAY ANDRIST, a citizen of the United States, residing at Mankato, in the county of Blue Earth and State of Minnesota, have invented a new and useful Camping Attachment for Motor Vehicles, of which the following is a specification.

This invention relates to a camping attachment adapted to be combined with an automobile, said attachment comprising a bed, a tent, and a luggage carrier, all of the parts being so constructed that they can be carried conveniently at a point out 10 side of the vehicle where they will not cause inconvenience to the persons riding within the machine.

Another object is to provide an outfit of this character which does not detract from 20 the appearance of the vehicle while the parts are collapsed but, on the contrary, has the appearance of and can be used as a luggage carrier.

Another object is to provide a structure 25 which can be set up quickly and will form a comfortable bed and an efficient shelter or tent.

With the foregoing and other objects in 30 view which will appear as the description proceeds, the invention resides in the combination and arrangement of parts and in the details of construction hereinafter described and claimed, it being understood that, within the scope of what is claimed, 35 changes in the precise embodiment of the invention shown can be made without departing from the spirit of the invention.

In the accompanying drawings the preferred form of the invention has been shown.

40 In said drawings

Figure 1 is a side elevation showing the outfit set up for use as a bed and tent.

Figure 2 is a plan view, the tent or shelter being removed.

45 Figure 3 is an end elevation of a portion of the tent and showing one of the side flaps extended to form a canopy.

Figure 4 is an enlarged section through 50 one of the side members of the bed frame and showing how the springs are attached thereto.

Figure 5 is a side elevation of the frame of the structure collapsed for use as a luggage carrier.

Figure 6 is a detail view of one end portion of one of the side rails.

Referring to the figures by characters of reference 1 designates one of the end members of the structure, the terminals of this member being adapted to be fastened by 55 clamps or other suitable devices, not shown, to the rear end of an automobile. From the end portions of this member extend parallel tubular arms 2 on which are secured blocks 3 having concaved seats 4 in their 60 upper faces from the centers of which project upstanding folding pins 5.

When the apparatus is set up for use these tubular arms are adapted to receive the reduced ends 6 of side rails 7, the rails 70 being preferably tubular and the reduced ends 6 being fastened in the arms 2 by bolts 8 one of which has been shown in Figure 1. Those ends of the side rails 7 remote from the arms 2 are adapted to receive rods 9 which can be fastened therein by bolts 10, these rods being extended from Y-connections 11. One member of each connection is extended upwardly when the apparatus is set up for use and has an 75 inclined post 12 mounted therein. Another member of each connection is extended downwardly and is engaged by a standard 13 which forms a leg when the parts are set up for use as shown in Figure 1. The 80 posts 12 have pins 14 extending from their free ends. The two Y-connections are connected by a cross member 15 and formed within this member, in the member 1, in the arm 2, and in the side rails 7 and the 90 rods 9 are openings 16 adapted to receive hooks 17 formed at the outer ends of coiled springs 18. The inner ends of these springs are attached to the edges of a bed bottom 19 formed of any suitable fabric.

95 A covering or tent has been indicated at 20 and one end of the top thereof is adapted to be buttoned or otherwise fastened to the rear portion of the top T of an automobile. The pins 14 are designed to extend through 100 openings in the top and the walls of the tent are designed to close the two sides and the

back end thereof as shown at 21. One of the side walls can be used as a canopy or sunshade by extending it laterally and downwardly away from the tent and supporting it with posts 22 having pins 23 extending through openings in the supported flap. This arrangement of parts has been shown both in Figures 1 and 3. By removing the posts 22 the supported flap can be lowered 10 and fastened.

As shown in Figure 1 blocks 24 corresponding with the blocks 3 can be secured to each rod 9, these blocks being provided with recesses or seats from which holding 15 pins 25 extend. These blocks are so positioned that they are supported under the rods 9 when the structure is set up as in Figure 1.

When it is desired to collapse the structure the tent covering is removed and formed into a compact bundle. The hooks 17 are withdrawn from the openings 16 and the bed bottom 19 together with the springs 18 is also compactly folded or rolled. The 25 side rails 7 are then detached from the arms 2 and the rods 9 and said rods are inserted into and secured within the arms 2 but with the standards 13 extended upwardly instead of downwardly. This arrangement has been 30 shown in Figure 5. The posts 12 are of course detached. With the parts thus arranged the side rails 7 are placed on certain of the blocks 3 and 24 so that the pins thereon will project into openings 26 formed in 35 the side rails. The posts 12 are also placed in certain of said seats, these posts being provided with openings 27 to receive certain of the holding pins. The posts 22 need not be parts of the apparatus but can be cut for 40 use from timber conveniently situated. With the parts assembled as shown in Figure 5 the folded tent and the bed bottom structure can be fastened on the members 7 and 15 and other articles can likewise be supported 45 on these members and between the vehicle bottom and the standards 13, the use of straps or ropes rendering the structure an efficient luggage carrier.

What is claimed is:—

50 1. A structure of the class described including an end member for attachment to a vehicle, side arms extending therefrom, a second end member, side rods extending therefrom for attachment to the side arms, standards extending from said second end member, the said member being reversible to position the standards for use either as supporting legs or as upstanding members, side rails insertible between and detachably connected to the arms and rods for holding the end members apart for use as bed frame, a bed bottom detachably connected to the end members and to the side rails, and means upon the arms and rods for engaging and 60 holding the side rails when arranged trans-

versely between the end members when the arms and rods are secured together.

2. The combination with an end member having side arms, of a second end member having side rods for detachably engaging 70 the side arms, standards extending from said second member, side rails interposed between and detachably secured to the arms and rods for holding the ends members spaced apart to form a bed frame, said 75 standards constituting supporting legs for the frame, a bed bottom detachably connected to the end members and side rails, said second end member being reversible and its rods attachable to the side arms to 80 form a luggage carrier, and means on the side arms for holding the side rails transversely of the luggage carrier.

3. The combination with an end member for attachment to a vehicle and side arms 85 extending therefrom, of a reversible end member, side rods extending therefrom, side rails adapted to be interposed between and secured to the arms and rods to form a bed frame, standards on the reversible member 90 constituting supporting legs for the bed frame, said reversible end member being reversible to extend the legs upwardly with the rods in engagement with the side arms thereby to form a luggage carrier, a bed 95 bottom, means for detachably connecting the same to the bed frame, and means on the arms and rods for supporting and engaging the side rails when the structure is collapsed for use as a luggage carrier. 100

4. The combination with an end member for attachment to a vehicle and side arms extending therefrom, of a reversible end member, rods extending therefrom, standards connected to the reversible end member, posts detachably engaging the reversible end member, side rails interposed between and secured to the arms and rods to form a bed frame, said standards constituting supporting legs for the bed frame, 105 the reversible end member being adapted to be reversed to extend the standards upward, the rods being shiftable into engagement with the arms, a bed bottom, means for detachably securing the bed bottom to 110 the end members and side rails, and means on the arms and rods for supporting and engaging the side rails and the posts when the rods are in engagement with the arms, thereby to form a luggage carrier, and a 115 tent cover adapted to be supported in extended position by the posts when mounted on the reversible end member.

5. The combination with fixed and movable end members, standards upon the movable end member, rods extending from said movable member and arms extending from the fixed member and detachably engaged by the rods, of side rails and posts mounted 120 on the arms and rods and cooperating with 125 130

the ends members to form a luggage carrier, posts and holding them in upstanding tent- 10
said movable end member being separable
from the fixed member and reversible,
means for securing the side rails between
5 the two end members when the movable
member is reversed, thereby to form a bed
frame, the standards constituting support-
ing legs for the frame, and means upon the
reversible end member for engaging the

In testimony that I claim the foregoing
as my own, I have hereto affixed my signa-
ture in the presence of two witnesses.
